REFLECTIVE BICYCLE PEDAL

Robert F. Humlong, Maysville, Ky., assignor to Wald Manufacturing Company, Inc., Maysville, Ky.

Filed Feb. 24, 1970, Ser. No. 21,579

Term of patent 14 years

Int. Cl. D12—14

U.S. Cl. D90—14

FIG. 1 is a top plan view of a reflective bicycle pedal showing my new design.

FIG. 2 is a side elevational view of the same.

FIG. 3 is an end elevational view of the right end thereof.

FIG. 4 is an end elevational view of the left end thereof.

FIG. 5 is a view of the same taken on either of lines 5—5 of FIG. 1.

FIG. 6 is a view of the same taken on line 6—6 of FIG. 2.

I claim:

The ornamental design for a reflective bicycle pedal, as shown.
